MERCURY SWITCH

Carl H. Larson, Elkhart, Ind., assignor to The
Adlake Company, a corporation of Illinois

Application January 12, 1939, Serial No. 250,521

23 Claims. (Cl. 200—112)

This invention relates primarily to mercury switches of the type in which a magnetically controlled plunger is mounted within a hermetically sealed envelope, containing mercury and spaced electrodes, to displace more or less mercury for changing the condition of the electrical circuit through the electrodes. The invention, however, is not limited in its use to mercury switches of this type, but may also be used in conjunction with tilting switches and even other types of mercury switches.

More specifically, the invention pertains to the construction of the intermittently immersed contact of a mercury switch, and among its principal objects are the following: To provide an electrode construction that will stand up almost indefinitely under all conditions of wear and usage; to produce a switch that will consistently give sharply defined makes and breaks; to form the electrode in such a manner that the operating characteristics of the switch with its associated relay coil may be controlled by slight variations in the electrode construction; to provide an electrode construction that will give uniform results, particularly in time delay relays; to increase the current carrying capacity for a switch of given size; and to provide an electrode construction that can be fabricated at low cost.

Further and other objects and advantages will become apparent as the disclosure proceeds and the description is read in conjunction with the accompanying drawing, in which

Fig. 1 is a sectional view of a fast acting plunger type mercury switch with a mercury to mercury contact, the central electrode consisting of a ceramic cup that is bonded to the glass sleeve surrounding the central electrode;

Fig. 2 is a fragmentary view showing a slightly modified form of central electrode;

Fig. 3 shows still another modification of the central electrode;

Fig. 4 is a fragmentary view showing a metal to mercury contact which incorporates some of the features of this invention;

Fig. 5 is a sectional view of a time delay relay embodying the present invention;

Fig. 6 is an enlarged view of the electrode construction shown in Fig. 5;

Fig. 7 shows a preferred electrode construction; and

Fig. 8 is a top plan view of the electrode construction shown in Fig. 7.

This application is a continuation in part of my earlier application, Ser. No. 82,855, filed June 5, 1936.

In a mercury switch, it is customary to have one electrode that is constantly in contact with the mercury fill and another electrode which is intermittently placed in contact with the mercury fill by some means for manipulating the

fill. The relative position of the fill with respect to the electrodes may be effected by tilting the switch envelope, or by displacing mercury by means of a magnetically controlled displacer.

When the mercury switch is being used for controlling circuits having a relatively heavy load, there is a tendency for the intermittently immersed electrode to become damaged by the intense heat and destructive effect of the arc formed at the instant when the circuit is opened or closed, and particularly when the circuit is being opened under an inductive load. Various attempts have been made to protect the electrode by the use of refractory materials, but none of these have the simplicity and effectiveness of the present invention. Another means for protecting the intermittently immersed electrode is by bending the bared end of the electrode over the insulating sleeve, as shown in my prior Patent No. 1,967,247.

The nature of the invention and its utility will become apparent by referring to Fig. 1 of the drawing in which one form of the invention is shown. The switch envelope 10 is made of glass and contains a quantity of mercury 11. A pair of electrodes 12 and 13 are sealed through the bottom of the electrode, the latter electrode being enclosed within a glass sleeve 14 for a portion of its height. The sleeve 14 has a bulge 15 which acts as a seat for a spring 16, the upper end of which is spread out as indicated at 17, to yieldingly restrain the displacer, generally designated 18, from striking the bottom of the switch envelope.

The displacer 18 comprises an inner sleeve 19 of glass, ceramic, or other light-weight non-magnetic material, and an outer sleeve 20 of magnetic material. The inner sleeve 19 has its lower end enlarged to form a shoulder 21 on which the outer sleeve 20 is mounted. Guide washers 25 are carried by the displacer for guiding its movement within the switch envelope, the top washer being held in place by a coil spring 26.

A ceramic cup 27 is mounted on the upper exposed end of the electrode 13. The cup contains a pool of mercury 28 which is in contact with the bared end of the electrode 13. In practice, the electrode assembly is made by first taking a suitable length of electrode wire 13, preferably of molybdenum, then telescoping the glass sleeve 14 over the wire, heating the two to bond the sleeve to the wire and to form the bulge 15, slipping the spring 16 into place on the bulge 15, then telescoping the ceramic cup 27, drilled at 22, over the bared end of the electrode 13, and finally bonding the cup 27 to the top of the sleeve 14. This latter step may be done by the use of a suitable adhesive but pref-

erably the materials for the glass sleeve 14 and the ceramic cup are chosen in accordance with the disclosure of my prior application, Ser. No. 82,855, filed June 1, 1936 (which application is hereby specifically made a part of the present disclosure), so that they may be fused together. When this method of bonding is used, sufficient heat is applied to cause the glass to flow into the interstices of the ceramic material and the result is a bond that is exceptionally strong. A bond of this kind also has the advantage that there is no opportunity for a short circuit to occur in the switch at the bond 23 since that bond is substantially the equivalent of a unitary structure.

A relay coil 29 is associated with the switch, and when the coil is energized, the displacer 18 is drawn downwardly, causing the mercury level to rise above the lower edge of the cup 27 and make contact with the mercury pool 28, thus closing the circuit between the electrodes 12 and 13 through the body of mercury 11. When the coil is de-energized, the displacer rises and the mercury level falls, thus breaking the circuit.

25 The cup or cap 27 is an integrally formed piece of ceramic material, such as Alundum (grade RA84, RA360 or RA98), which, I am informed, is substantially pure Al_2O_3 . It is a product of the Norton Company, Worcester, Massachusetts. The cap 27 is preformed into its desired shape, preferably by being molded, and the passageway 22 is of a size which permits the cap to tightly telescope the bared end of the electrode 13.

35 It has been found that when the cup 27 is provided with a flat horizontal rim as distinguished from the sloping rim 35 shown in Fig. 1, there is a tendency for the mercury 28 within the cup to cling to the main body of mercury 11 at the instant that the circuit is being broken, with the result that the break is not clean, or in other words, it is characterized by a "chatter." Presumably this is caused by the fact that the mercury 28 in the cup 27 at the instant when 40 the mercury fill 11 has been lowered by the displacer 18 to a point where it is about to separate from the mercury pool 28, is connected to the main body of the fill 11 on all sides, so that when the mercury fill 11 is lowered to the extent 45 that a break is caused, the break does not occur instantaneously on all sides of the cup, but instead occurs on one side only, causing the mercury 28 in the cup to snap back to the other side of the cup and prolong the time required 50 for the breaking of the circuit. This "snap-back" action is not smooth, and it usually produces a series of breaks on the side of the cup toward which the movement of mercury is directed, and this characteristic jagged break or 55 chatter is clearly indicated on high speed photographs or similar equipment.

The same characteristic action takes place in the electrode structure shown in Fig. 2 in which the rim of the cup has a double slope providing 60 low points 36 and 37 along the rim. Obviously the break will first take place at one or the other of these two low points, and the snap back action of the mercury in the cup will produce a more or less jagged break of the circuit on 65 the other side of the cup, but the action is not nearly as pronounced as with a cup having a horizontal flat rim.

These unfavorable switch characteristics are avoided by the use of a single sloped cup such 70 as shown in Fig. 1, in which the break between

the two bodies of mercury is confined to a relatively small portion of the rim of the cup 27. The cup is truncated, as shown at 35, providing a low portion 39 which invariably is the edge over which the break occurs. Any snap back 5 action of the mercury in the cup 27 is directed against the opposed wall 40 of the cup and this wall is sufficiently high so that the mercury 28 cannot be thrown over the wall by the rush of mercury to the left (Fig. 1) at the instant when 10 the connection between the body of mercury in the cup 27 and the mercury fill 11 in the switch envelope 10 is broken.

The same result may be accomplished by using a cup 41 (Fig. 3) having a horizontal rim 42 15 provided with a cut-out portion 43. Obviously when the level of the mercury body 11 falls away from the rim 42 of the cup, the break between the body of mercury in the cup and the main mercury fill will occur over the edge 44 and the 20 opposite wall being considerably higher will prevent the mercury from slinging over to cause chattering on the breaking of the circuit.

Electrodes of the mercury cup type, when constructed according to the teachings of this invention to localize the break at a depressed portion of the rim, also have the advantage that they enable the switch as a whole to operate on relatively small differences between pickup and drop-away values for the associated relay coil, 25 particularly when considering the usual relatively high differences between these values in relays using mercury to mercury contacts. For example, a switch using an electrode provided with a horizontal flat rim (but without a depressed portion as in Fig. 3) would have a relatively high differential between pickup and drop-away values.

By varying the angle of the sloping rim 35, the span between pickup and drop away values 40 may be controlled. When the angle is very steep, the span is relatively low, and when the angle is small (i. e.) approaching the horizontal, the span is relatively large.

The same control of the span may be effected 45 in the electrode construction shown in Fig. 3 by varying the width of the cut-out portion 43. When a relatively large section is cut away, the span between pickup and drop-away values is correspondingly large.

50 A time delay switch is shown in Fig. 5 which illustrates other features of the invention. The switch comprises an envelope 50 containing a mercury fill 51. Conductors 52 and 53 are sealed through the base of the envelope and are covered for a portion of their lengths by insulating sleeves 54 and 55, respectively. The latter is cut away, as indicated at 56, so that the conductor 53 is in constant contact with the mercury fill 51. Fused to the upper ends of the 55 sleeves 54 and 55 is a glass thimble 57 provided at its upper portion with a porous wall 58 preferably of ceramic material such as Alundum, and having a relatively large opening 59 for admitting mercury to the interior of the 60 thimble. The conductor 52 with its insulating sleeve 54 extends upwardly into the thimble 57, the sleeve being enlarged at its upper end as indicated at 60 to provide a seat for the ceramic cup 61 which surrounds the exposed end 62 of 65 the conductor 52. The cup 61 is preferably a preformed ceramic piece cut from cylindrical tubing and the cup is suitably bonded to the enlarged head 60 of the sleeve 54.

70 The displacer 63 is similar to the displacer

18 in Fig. 1 and when it is pulled down by the associated relay coil, a given quantity of mercury is displaced which normally raises the outside mercury level to at least the upper end 64 of the thimble 57, although the admission of mercury to the interior of the thimble 57 is restrained by the slow escapement of gas trapped within the thimble through the pores of the ceramic plug 58.

10 When the displacer 63 is released by the coil, it immediately rises to the position shown in Fig. 5, and the outside mercury level falls to a point well below the upper margin 65 of the opening 59, with the result that the mercury in the thimble 57 immediately falls from the thimble, breaking the circuit between the electrodes 52 and 63.

15 In normal operation of the switch, the displacer 53 is held down by the relay coil for a sufficient time to permit the mercury entering the thimble 57 to reach the top of the thimble so that all gas is expelled from the thimble. It sometimes happens, however, that the relay coil is de-energized before the mercury level has had a chance to completely fill the thimble, and in 20 such a case, the amount of mercury which rushes by the cup 61 when the circuit is being broken is substantially less than the head of mercury which passes the cup when the displacer is released following a complete filling of the thimble 57. The result is that when the thimble is emptied subsequent to a complete filling of the thimble with mercury, the amount of mercury remaining in the cup 61 may be represented by the dotted line 66 in Fig. 6 whereas the amount 25 of mercury remaining in the cup when the thimble is emptied subsequent to a partial filling of the thimble is represented by the full line 67 in Fig. 6. Obviously, this difference in the amount of mercury left in the cup affects the 30 time delay characteristics of the switch and produces a certain amount of non-uniformity even though it has the advantages of the electrode structure shown in Fig. 1 and the additional advantage arising from the ease with which it can be fabricated from cylindrical tubing stock of 35 ceramic material.

40 I have found that I can eliminate this undesirable variation in timing by using the electrode structure shown in Figs. 7 and 8. This 45 structure differs from that shown in Fig. 5 in two respects: First, in that the conductor 52 extends above the maximum mercury level contained within the cup 68 and second, in that the bared end 69 of the conductor 52 is eccentrically positioned within the cup 68.

Both of these features have advantages which 50 make them useful in fast acting switches as well as slow acting switches, and for this reason, the electrode structure of Figs. 7 and 8 constitutes a preferred form of the invention. By 55 having the bared end 69 of the electrode 52 extending above the maximum mercury level within the cup 68 a sufficient amount, the contact resistance between the mercury and the exposed end 69 of the electrode 52 may be made substantially equal to or less than the resistance of the conductor 52 itself. In other words, by 60 extending the bared end 69 of the conductor 52 a sufficient distance, it is possible to have the area of the contact between the bared end 69 and the mercury in the envelope of such extent that the resultant contact resistance is substantially equal to or less than the resistance of the electrode 52, with the result that there is no 65 tendency for the mercury in contact with the

electrode 69 to become hot, or at least any hotter than the sleeve 54 surrounding the conductor 52. This feature of the electrode construction makes it particularly desirable for use in all types of mercury switches.

The extension of the conductor 52 above the maximum mercury level in the cup 61 has another distinct advantage, particularly when the electrode is used in a time delay relay such as the one shown in Fig. 5. It has been found that 10 when the bared end 62 (Fig. 5) of the electrode 52 projects above the mercury in the cup 61, the difference between the mercury level 66 and 15 67 in Fig. 6 resulting from abnormal operating conditions is greatly reduced. Presumably this 20 phenomenon is due to the change in surface tension occasioned by the projection of the electrode 25 62 through the mercury fill in the cup 61.

When the bared end of the electrode 52 is placed eccentrically within the surrounding cup, 20 as for example in Figs. 7 and 8, the cup can have a smaller inside diameter without affecting the ability of the cup to fill after it has been emptied, as, for example, after the switch has been turned upside down. This means that the 25 overall diameter of a switch having a given current carrying capacity can be held to a minimum. By way of example, the cup 68 in Fig. 7 will fill consistently and easily when the diameter of the electrode 69 is 60 mils, and the cup 30 has an inside diameter of $\frac{3}{8}$ of an inch. A cup of the same size will not fill satisfactorily when the electrode is centrally positioned as shown in Figs. 5 and 6.

The eccentric positioning of the electrode 69 35 within the cup 68 (Fig. 7) and the resultant ability to reduce the inside diameter of the cup 68 has the additional advantage that the quantity of mercury remaining in the cup 68 is always 40 the same, even though the relay is operated under the conditions which produce the abnormal high level 67 shown in Fig. 6, so that the accuracy of a time delay relay using the electrode structure shown in Figs. 7 and 8 is improved over a 45 switch using the electrode structure shown in Figs. 5 and 6.

In all forms of the invention, the electrode structure is characterized by its ability to withstand the deteriorating effect of the electric arc and produce uniform, sharply defined makes and 50 breaks to varying degrees.

All forms of the invention also are characterized by the ease with which the electrode structure can be fabricated.

I claim:

1. In a mercury switch, a switch envelope, a quantity of mercury in the envelope, spaced electrodes in the envelope, one of which projects upwardly through the mercury and is covered for a portion of its length by a sleeve of insulating 60 material leaving a bared end, means for manipulating the mercury fill to bridge and unbridge the electrodes with mercury, and an integrally formed cap of refractory material surmounting the insulating sleeve and bonded to it, said cap 65 including a stem portion which tightly telescopes the bared end of the electrode.

2. In a mercury switch, a switch envelope, a quantity of mercury in the envelope, spaced electrodes in the envelope, one of which projects upwardly through the mercury and is covered for a portion of its length by a sleeve of insulating 70 material leaving a bared end, means for manipulating the mercury fill to bridge and unbridge the electrodes with mercury, and an integrally 75 formed cap of refractory material surmounting the insulating sleeve and bonded to it, said cap including a stem portion which tightly telescopes the bared end of the electrode.

formed cap of refractory material surmounting the insulating sleeve and bonded to it, said cap including a stem portion which tightly telescopes the bared end of the electrode, and a cup portion 5 adapted to contain a quantity of mercury.

3. In a mercury switch, a switch envelope, a quantity of mercury in the envelope, spaced electrodes in the envelope, one of which projects upwardly through the mercury and is covered for 10 a portion of its length by a sleeve of insulating material leaving a bared end, means for manipulating the mercury fill to bridge and unbridge the electrodes with mercury, an integrally formed cap of refractory material surmounting the insulating sleeve and bonded to it, said cap including a stem portion which tightly telescopes the bared end of the electrode, and a cup portion 15 adapted to contain a quantity of mercury, the cup portion having a part of its rim lower than the remainder so that the bridging and unbridging of the electrodes by mercury will take place across said depressed part of the cup.

4. In a mercury switch, a switch envelope, a mercury fill, spaced conductors in the envelope 25 including an electrode projecting upwardly through the fill and covered for a portion of its length by a glass sleeve leaving the end of the electrode exposed, a cup mounted on the sleeve, encircling the exposed end of the electrode and 30 adapted to contain mercury, said cup being of a material more highly refractory than glass, and a magnetically responsive plunger for shifting the level of the mercury fill.

5. In a mercury switch, a switch envelope, a 35 mercury fill, spaced electrodes in the envelope, one of which projects upwardly through the mercury fill and is covered for a portion of its length by an insulating sleeve leaving a bared end, a cup surmounting the sleeve and bonded to it providing a receptacle for mercury in constant contact 40 with said bared end of the electrode, means for moving the mercury fill to and away from said electrode, said cup having a portion of its rim lower than the remaining portion whereby 45 the electrical contact between the body of mercury in the cup and the body of mercury in the envelope is broken across said lower portion of the rim.

6. In a mercury switch, a switch envelope, a 50 mercury fill, spaced electrodes in the envelope, one of which projects upwardly through the mercury fill and is covered for a portion of its length by an insulating sleeve leaving a bared end, a cup surmounting the sleeve and bonded to it providing a receptacle for mercury in constant contact 55 with said bared end of the electrode, means for moving the mercury fill to and away from said electrode, the rim of said cup having a depressed portion whereby the electrical contact 60 between the body of mercury in the cup and the body of mercury in the envelope is broken across said depressed portion of the rim.

7. In a mercury switch, a switch envelope, a 65 mercury fill, spaced conductors in the envelope including an electrode projecting upwardly through the fill and covered for a portion of its length by an insulating sleeve leaving the end of the electrode exposed, a truncated cup surmounting the sleeve and encircling the exposed end of 70 the electrode and containing mercury, and means for shifting the mercury level in the envelope toward and away from the exposed end of the electrode.

8. In a mercury switch, a switch envelope, a 75 quantity of mercury within the envelope, spaced

electrodes in the envelope, one of which projects upwardly through the mercury fill and is surrounded for at least a portion of its length by a sleeve of insulating material closed below its upper end to form a cup adapted to retain mercury in constant contact with said one electrode, at least a portion of said sleeve comprising a section of tubing of substantially uniform cross section formed of a ceramic material having highly refractory and arc resistant properties and the upper end of said cup being above the low mercury level, and magnetically responsive means for shifting the mercury fill to bridge and unbridge the electrodes with mercury. 5

9. In a mercury switch, a switch envelope, a 10 mercury fill, spaced conductors in the envelope including an electrode projecting upwardly through the fill and covered for a portion of its length by an insulating sleeve leaving the end of the electrode exposed, a mercury filled cup surmounting the sleeve and encircling the exposed end of the electrode, means for shifting the mercury level in the envelope toward and away from the exposed end of the electrode, said electrode being of sufficient height so that its exposed end 15 projects above the mercury in the cup when the electrical circuit through the conductors is open. 20

10. In a mercury switch, a switch envelope, a mercury fill, spaced electrodes in the envelope, one of which projects upwardly through the mercury fill and is covered for a portion of its length by an insulating sleeve leaving a bared end, a cup 25 surmounting the sleeve and bonded to it providing a receptacle for mercury in constant contact 30 with said bared end of the electrode, means for moving the mercury fill to and away from said electrode, the bared portion of said electrode being sufficient in extent so that the contact resistance between the mercury in the envelope 35 and the electrode when the switch is closed, is substantially equal to or less than the cross sectional resistance of the electrode itself.

11. In a mercury switch, a switch envelope, a mercury fill, spaced conductors in the envelope including an electrode projecting upwardly 45 through the fill and covered for a portion of its length by an insulating sleeve leaving the end of the electrode exposed, a mercury filled cup surmounting the sleeve and encircling the exposed end of the electrode, means for shifting the mercury level in the envelope toward and away from the exposed end of the electrode, said electrode being extended above the lowest point of the cup rim whereby a sharp clean-cut break of the electrical circuit between the conductors is effected 50 when the mercury level in the switch envelope is dropped.

12. In a mercury switch, a switch envelope, a mercury fill, spaced conductors in the envelope including an electrode projecting upwardly 60 through the fill and covered for a portion of its length by an insulating sleeve leaving the end of the electrode exposed, a cup mounted on the sleeve and encircling the exposed end of the electrode and containing mercury, means for shifting the mercury level in the envelope toward and away from the exposed end of the electrode, said electrode being eccentrically positioned within the cup. 65

13. In a mercury switch, a switch envelope, a 70 mercury fill, spaced conductors in the envelope including an electrode projecting upwardly through the fill and covered for a portion of its length by an insulating sleeve leaving the end of the electrode exposed, a mercury filled cup sur- 75

- mounting the sleeve and encircling the exposed end of the electrode, means for shifting the mercury level in the envelope toward and away from the exposed end of the electrode, said cup having a portion of its rim depressed whereby the electrical circuit between the conductors is normally broken across the depressed portion of the rim, and said exposed end of the electrode being eccentrically positioned within the cup on the opposite side of said depressed portion of the rim.
14. In a mercury switch, a switch envelope, a mercury fill, spaced conductors in the envelope including an electrode projecting upwardly through the fill and covered for a portion of its length by an insulating sleeve leaving the end of the electrode exposed, said sleeve being provided with an enlargement, and a tube of ceramic material bonded to the enlarged portion of the sleeve and forming a cup around the bared end of said electrode.
15. In a mercury switch, a switch envelope, a mercury fill, spaced conductors in the envelope including an electrode projecting upwardly through the fill and covered for a portion of its length by an insulating sleeve leaving the end of the electrode exposed, a mercury filled cup surmounting the sleeve and encircling the exposed end of the electrode, means for shifting the mercury level in the envelope toward and away from the exposed end of the electrode, means for restraining the movement of mercury away from said cup, the bared end of the electrode within the cup extending above the lowest point of the cup rim.
- 33 16. In a mercury switch, a switch envelope, a mercury fill, spaced conductors in the envelope including an electrode projecting upwardly through the fill and covered for a portion of its length by an insulating sleeve leaving the end of the electrode exposed, a mercury filled cup surmounting the sleeve and encircling the exposed end of the electrode, means for shifting the mercury level in the envelope toward and away from the exposed end of the electrode, means for restraining the movement of mercury away from said cup, the bared end of the electrode within the cup extending above the lowest point of the cup rim and being eccentrically positioned with respect to the cup.
- 50 17. In a mercury switch, a switch envelope, a quantity of mercury in the envelope, spaced electrodes in the envelope, one of which projects upwardly through the mercury and is covered for a portion of its length by a sleeve of insulating material leaving a bared end, means for manipulating the mercury fill to bridge and unbridge the electrodes with mercury, and an integrally formed cap of refractory material mounted on the insulating sleeve and bonded to it, said cap being in the form of tubing and being telescoped over at least a part of the bared end of the electrode.
- 65 18. In a mercury switch, a switch envelope, a mercury fill, contact means including an electrode projecting into the envelope, an insulating sleeve telescoped over said electrode, at least the upper portion of said sleeve being formed of highly refractory, arc resistant, ceramic material, and being adapted to retain a quantity of mercury in continuous contact with said electrode and having a portion of its rim lower than the remaining portion, the lowest portion of said rim being above the low level of the mercury, and a magnetically responsive displacer within
- said envelope to shift the mercury fill into and out of electrical contact with the mercury retained by said sleeve.
19. In a mercury switch, a switch envelope, a mercury fill, spaced conductors in the envelope, including an electrode projecting upwardly through the fill and covered by an insulating sleeve, the end of said electrode being exposed and surrounded by substantially cylindrical insulating means capable of retaining a quantity of mercury in continuous electrical contact with said electrode, and a magnetically responsive displacer for shifting the mercury level in the envelope toward and away from the exposed end of the electrode, said insulating means having a portion of its rim depressed, whereby the electrical circuit between the conductors is normally broken across the depressed portion of the rim.
20. In a mercury switch, a switch envelope, a mercury fill, spaced conductors in the envelope including an electrode projecting upwardly through the fill and covered for a portion of its length by an insulating sleeve, leaving the end of the electrode exposed, a mercury filled cup encircling the exposed end of the electrode, means for shifting the mercury level in the envelope toward and away from the exposed end of the electrode, said cup having a portion of its rim depressed, whereby electrical circuit between the conductors is normally broken across the depressed portion of the rim.
- 25 21. In a mercury switch, a switch envelope, a mercury fill, spaced electrodes in the envelope including an electrode projecting upwardly through the fill and covered for a portion of its length by an insulating sleeve leaving the end of the electrode exposed, a tubular member mounted on the sleeve and encircling the exposed end of the electrode, and means for shifting the mercury level in the envelope toward and away from the exposed end of the electrode, said electrode being eccentrically positioned within the tubular member.
- 35 22. In a mercury switch, a switch envelope, a mercury fill, spaced electrodes in the envelope, one of which projects upwardly through the mercury fill, and is covered for a portion of its length by an insulating sleeve leaving a bared end, a cup surmounting the sleeve providing a receptacle for mercury in constant contact with said bared end of the electrode, means for moving the mercury fill to and away from said electrode, said cup having at least two portions of its rim lower than the remaining portions, whereby electrical contact between the body of the mercury in the cup and the body of the mercury in the envelope is broken across said lower portions.
- 45 23. In a mercury switch, a switch envelope, a mercury fill, spaced conductors in the envelope one of which projects upwardly through the mercury fill and is covered for a portion of its length by an insulating sleeve, leaving a bared end, a cup surmounting the sleeve providing a receptacle for mercury in constant contact with said bared end of the electrode, means for moving the mercury fill to and away from said electrode, the rim of said cup sloping in two directions defining depressed portions in said rim, whereby the electrical contact between the body of mercury in the cup and the body of mercury in the envelope is broken across said lower portions of the rim.

CARL H. LARSON.

CERTIFICATE OF CORRECTION.

Patent No. 2,232,874.

February 25, 1941.

CARL H. LARSON.

It is hereby certified that error appears in the printed specification of the above numbered patent requiring correction as follows: Page 5, second column, line 33, claim 21, for the word "electrodes" read --conductors--; line 59, claim 23, for "conductors" read --electrodes--; and that the said Letters Patent should be read with this correction therein that the same may conform to the record of the case in the Patent Office.

Signed and sealed this 25th day of March, A. D. 1941.

Henry Van Arsdale,
Acting Commissioner of Patents.
